Application May 1, 1952, Serial No. 285,408

Claims priority, application Netherlands May 23, 1951

8 Claims. (Cl. 179—16)

This invention relates to electronic dialling circuits for automatic signalling systems, for example, telephone systems, for the numerical establishment of a connection between one of a plurality of apparatus of a first kind, for example a connecting circuit, and one of a plurality of apparatus of a second kind, for example a subscriber's line circuit or a subsequent dialling stage, each having associated with it a number or a figure.

A circuit has been suggested, in which such a connection may be established with the use of gas-filled discharge tubes, for example, cold cathode tubes. In this circuit a multiplied point of each apparatus of the first kind is connected by way of an impedance to a first terminal of a source of supply and also coupled by way of a discharge path of a gaseous tube to a multiplied point of each apparatus of the second kind. Each multiplied point is connected by way of an impedance to a second terminal of the source of supply. The difference in potential between the terminals of the source of supply is smaller than the ignition voltage of the discharge paths, but greater than the operating voltage. Provision is also made of a marking circuit for receiving dialling signals transmitted by a subscriber, an input control-point of said marking circuit being connected to the multiplied point of the apparatus of the first kind, which point may have supplied to it dialling pulses. A plurality of marking output points are coupled to ignition electrodes of the gaseous tubes, which are connected to the multiplied point of the apparatus of the first kind. The voltage of the marking point connected to the ignition electrodes of the gaseous tube associated with an apparatus of the second kind corresponding to the number is increased as a function of the number dialled to such extent that the gaseous tube concerned may become conductive if the apparatus is free, that is to say, if none of the other gaseous tubes connected to the multiplied point of the said apparatus is conductive. However, the gaseous tube cannot become conductive if the apparatus is busy, since in this case the voltage of the multiplied point differs from the voltage of the second terminal of the source of supply and is active at at least one of the electrodes of the gaseous tube, for example the ignition electrode or the cathode, in such manner that the ignition voltage cannot be exceeded.

As a rule, it is desirable in such dialling circuits that it should be possible to utilize an electronic counting circuit, for example a counting circuit comprising gaseous tubes or an electron-beam counting tube, as a marking switch. In this case the difficulty arises that steps must be taken to avoid undesired ignition of a gaseous tube during a series of dialling pulses or upon occurrence of pulses at the multiplied point of the apparatus of the first kind due, for example, to the extinction or ignition of a gaseous tube or to a call being answered.

The object of the invention is to avoid the above-described drawbacks and to provide an improved electronic dialling circuit for an automatic signalling system.

The invention will now be described with reference to the example thereof shown in the accompanying diagrammatic drawing.

The figure shows a circuit for a telephone system in which the speech connections between the subscribers such, for example, as AA, AB, AC, are established with the use of gas-filled tubes BA, BB, BC, the control of which is effected wholly by electronic means. In this system, each subscriber's line is coupled with the use of a gas-filled tube to a common point P of each of a plu-

2

rality of connecting circuits. For the sake of simplicity, the figure shows only three subscriber's stations AA, AB, AC with the associated line current paths LCA, LCB, LCC and a single connecting circuit VC. The line current paths of lines which are not shown, are exactly similar to the line circuits LCA, LCB, LCC, whilst the coupling of the subscriber's station AA, AB, AC with connecting circuits which are not shown is effected in a manner exactly similar to the coupling with the connecting circuit VC.

Each subscriber's station AA, AB, AC is connected across two primary windings of a transformer TA, TB, TC, respectively, the junction between the two primary windings of a transformer being by way of a source of supply V₂. One of the extremities of a secondary winding of TA, TB, TC is connected to earth by way of a parallel combination of a resistor R_{1a}, R_{1b}, R_{1c} and a capacitor C_{1a}, C_{1b}, C_{1c}, respectively. The other extremity of the secondary winding is connected to the cathode k of the gaseous tube BA, BB, BC, through which the line is coupled to the connecting circuit VC. The cathodes of gaseous tubes (not shown) by which the lines are coupled to the other connecting circuits, are connected in a similar manner to the multiplied points A, B, C of the line circuits. The anode a of the tube BA, BB, BC is connected to the common point P in the connecting circuit VC, which point is connected by way of an inductor L₁ and the parallel combination of resistor R₁ and capacitor C₁ to the point of supply V₁, the potential of which is higher than the operating voltage of the gas-filled tube BA, BB, BC, but lower than the ignition voltage between cathode k and anode a. The ignition voltage is for example, 170 volts and the operating voltage is 60 volts. The voltage V₁ may then, for example, be 140 volts.

Each gas-filled tube BA, BB, BC, comprises two ignition electrodes f₁ and f₂. The ignition voltage between the ignition electrodes f₁ or f₂ and the cathode of a tube is 70 volts.

The ignition electrodes f₁ are connected to tappings on high-ohmic voltage dividers R_{4a}, R_{5a}, and R_{4b}, R_{5b} and R_{4c}, R_{5c}, respectively, which are included

between a junction point Q, between inductor L₁ and resistor R₁, and supply source V₇, such that the difference in potential between each ignition electrode f₁ and the associated cathode k is slightly lower than the ignition

voltage, if none of the tubes BA, BB, BC connected to point P is conductive. The normal voltage of the ignition electrodes f₁ is, for example, 80 volts. The normal voltage of the ignition electrodes f₂ is equal to earth potential and hence much lower than the normal voltage of the ignition electrodes f₁.

The tubes BA, BB, BC may serve to establish a connection between a calling line and a connecting circuit and also for the numerical establishment of a connection between the connecting circuit and a calling line.

It is assumed that the subscriber at station AA having the number 2 wants to establish a connection with the subscriber at station AB having the number 3. When the subscriber at station AA lifts his handset, the line loop is closed through the apparatus at station AA, so that a strong negative voltage pulse is produced across the secondary winding of transformer TA. While only one tube BA is shown connected to point A, it is to be understood that a plurality of like tubes BA may be connected to point A. The voltage difference between the ignition electrodes f₁ and the cathodes k of the tubes BA, which couple the station AA to free connecting circuits, thus exceeds the ignition voltage, so that all the tubes BA can become conductive. The ignition electrodes f₁ of tubes BA, which couple the multiplied point A to busy connecting circuits VC, have a lower potential, since the potential of the points Q of the said connecting circuits is lower than that of V₁, which prevents the tubes from being ignited. As soon as one of the tubes

BA starts to become conductive, the main discharge path between the cathode k and the anode a of this tube BA also ignites, so that current starts to flow from the supply point V₁ by way of resistor R₁, inductor L₁, common point P, discharge path between anode a and cathode k of the tube BA, multiplied point A, secondary winding of transformer TA, and resistor R_{1a} to earth. A voltage

drop thus occurs across the resistors R_{1a} , R_1 , so that the potential of the multiplied point A increases by 40 volts and the potential of the point Q decreases by 40 volts. The increase in the potential of point A results in the difference in potential between the cathode k and the ignition electrode f_1 of the tubes BA becoming smaller than the ignition voltage, so that the said other tubes cannot ignite. Consequently, one tube BA only is ignited.

Due to the decrease in the potential of point Q, the potential of the ignition electrode f_1 of the tubes which couple the connecting circuits to other subscribers' lines also decreases. Consequently, it is avoided that upon a subsequent call by one of the other subscribers, one of the said tubes could ignite and this subscriber could also engage the connecting circuit VC, in other words the connecting circuit is marked busy by the decrease in the potential of point Q.

The subscriber AA subsequently dials the desired number, in this case the figure 3. The subscriber's dial is shunted by an impedance (not shown). With each dialling pulse the line loop is interrupted incompletely, so that the pulses which occur, during dialling, across the primary winding of transformer TA are smaller than the pulses which occur across the primary winding by closing or opening the line loop when the telephone is removed or replaced. Due to the differentiating action of transformer TA, a positive pulse occurs at the beginning of each dialling pulse and a negative pulse occurs at point A at the end of each dialling pulse. The amplitude of said pulses is approximately 5 volts. The pulses are transferred by way of the discharge path between cathode k and anode a of tube BA and inductor L_1 to the point Q and thence transferred by way of a capacitor C_9 to the control grid of a vacuum amplifying tube B_1 , by which said pulses are amplified and supplied with opposite polarity to a point U. The cathode of tube B_1 is connected to earth by way of a resistor R_3 , the anode being supplied by way of resistor R_2 from the source of supply V_1 . With each dialling pulse, transient positive and negative pulses of comparatively small amplitudes thus occur successively at the point U. The negative pulse has no effect. The positive pulse is supplied by way of capacitor C_2 to the ignition electrode f of a gas-filled discharge tube B_4 , which electrode is connected by way of resistor R_4 to a source of supply V_3 , the voltage of which is such that the gaseous tube B_4 becomes conductive if a small positive pulse is supplied to the point U. The positive pulse at the point U is furthermore supplied by way of capacitor C_3 and resistor R_5 to the ignition electrode f of a gas-filled discharge tube B_5 , which ignition electrode is coupled by way of resistor R_6 to a source of supply V_4 , the voltage of which is so much lower than that of the source of supply V_3 that the tube B_5 can ignite only with a much stronger positive pulse at the point U. Consequently, tube B_5 does not ignite upon reception of dialling pulses.

The anode a of tube B_4 is connected to the source of supply V_1 . The gaseous tube B_4 becomes conductive with the first dialling pulse. The cathode of this tube is connected to earth by way of an impedance Z_4 , constituted by an inductor in series with a resistor shunted by a capacitor. The elements of said impedance are chosen to be such that the gaseous tube B_4 cannot operate in a stable manner, but extinguishes again immediately after ignition. Similar impedances Z_2 , Z_3 , Z_5 are included for the same purpose in the cathode leads of the gas-filled discharge tubes B_2 , B_3 , B_5 .

When tube B_4 becomes conductive, a positive pulse occurs at the cathode k of this tube, which pulse is transferred by way of capacitors C_{11} , C_{12} , C_{13} , C_{1n} to the ignition electrodes f of the gas-filled discharge tubes B_{11} , B_{12} , B_{13} , B_{1n} of an electronic counting circuit MS of a kind known per se, which constitutes part of the VC.

The anodes a of the tubes B_{11} , B_{12} , B_{13} , B_{1n} are connected to the source of supply V_1 , the cathodes k being connected by way of resistors R_{11} , R_{12} , R_{13} , R_{1n} to a common point W, which is connected to earth by way of a resistor R_{33} . The ignition electrode f of tubes B_{11} is connected to a tapping point on a voltage divider R_{31} , R_{32} , included between earth and the source of supply V_1 . The cathodes k of the tubes B_{11} , B_{12} , B_{13} , B_{1n} are coupled by capacitors C_{21} , C_{22} etc. Furthermore, the ignition electrodes f of the tubes B_{12} , B_{13} etc. are connected

5 by way of resistors R_{21} , R_{22} etc. to the cathode of the preceding tube. The gaseous tubes are cut off in the normal condition of the circuit, the control electrode f of tube B_{11} having a potential higher than that of the ignition electrodes of the other tubes.

10 Since the tube B_4 becomes conductive with each dialling pulse, a positive voltage pulse is supplied to the ignition electrode of all gaseous tubes B_{11} etc. of the counting circuit MS. Since the ignition electrode of tube B_{11} has a normal potential higher than that of the other ignition electrodes, B_{11} only ignites. The voltage of the ignition electrodes of the other tubes remains below the ignition voltage. Consequently, a current starts to flow from the source of supply V_1 by way of the discharge path between anode a and cathode k of tube B_{11} and by way of resistor R_{33} to earth, so that the potential of the point W increases and the difference in potential between the ignition electrode and the cathode of tube B_{11} decreases. The potential of the ignition electrode of tube B_{12} increases more than the potential of the cathode due to the voltage drop across the resistor R_{11} .

15 After the first dialling pulse, the tube B_{11} only has become conductive and tube B_{12} is prepared for subsequent ignition. The tube B_{12} does not ignite with the first dialling pulse, since upon an increase in the potential of the cathode of tube B_{11} a positive voltage pulse is supplied to both the cathode of tube B_{12} by way of capacitor C_{21} and to the ignition electrode of tube B_{12} by way of resistor R_{21} , said pulses counteracting one another.

20 With the second dialling pulse, the tube B_4 becomes conductive for the second time and supplies a second positive pulse by way of capacitors C_{11} , C_{12} , C_{13} etc. to the ignition electrodes f of all gaseous tubes of the counting circuit MS. Since the ignition electrode of tube B_{12} , as a result of the increase in potential of the cathode of tube B_{11} , now has the highest potential of the ignition electrodes of the counting tubes, the gaseous tube B_{12} becomes conducting with the second counting pulse, with the result that the potential of the cathode k of tube B_{12} increases. Now, a positive voltage pulse is transferred by way of capacitor C_{21} to the cathode k of tube B_{11} , so that this tube extinguishes. After the second dialling pulse, the ignition electrode f of tube B_{12} has the highest potential of the ignition electrodes, since this ignition electrode is coupled by way of resistor R_{22} to the cathode of tube B_{12} , so that tube B_{13} is now prepared for subsequent ignition. Similarly, with the third dialling pulse, tube B_{13} is ignited and tube B_{12} extinguishes.

25 Consequently, tube B_{11} is conductive after one dialling pulse, tube B_{12} is conductive after two dialling pulses, tube B_{13} after three dialling pulses, etc. Each tube thus corresponds to a determined figure. Each ignition electrode f_2 of the tubes BA, BB, etc. is coupled by way of an integrating network constituted by resistors R_{2a} , R_{3a} and capacitors C_{2a} , C_{3a} and resistors R_{2b} , R_{3b} and capacitors C_{2b} , C_{3b} etc. respectively, to the cathode of the tube of the counting circuit MS which numerically corresponds to the number of the line with which the tube BA or BB is associated. Thus, for example, the ignition electrode f_2 of tube BB, which corresponds to the subscriber's station AB and which has associated with it the number 3 is coupled to the cathode of tube B_{13} , which is ignited after three dialling pulses. Similarly, the ignition electrodes f_2 of the tubes BC and BA, which correspond to subscribers' stations having associated with them, the numbers 1 and 2 are coupled to the cathodes of the tubes B_{11} and B_{12} respectively.

30 35 40 45 50 55 60 65 70 75 80 85 90 If one of the tubes B_{11} , B_{12} , etc. of the counting circuit is conductive, the voltage of the point W and hence the voltage of the cathodes of the other tubes is 40 volts. This voltage is lower than the ignition voltage between ignition electrodes f and cathode k of the tubes BA, BB, BC. The voltage of the cathode of the conductive tube is 80 volts and hence higher than the said ignition voltage.

40 45 50 55 60 65 70 75 80 85 90 With the first dialling pulse, the tube B_{11} ignites and the voltage of its cathode increases to 80 volts. Tube BC does not ignite, however, since the voltage of the ignition electrode f_2 cannot suddenly change to 80 volts, but can increase only comparatively slowly as a result of the integrating action of the network R_{2c} ,

C_{2c} , R_{3c} , C_{3c} . With the second dialling pulse, the tube B_{11} extinguishes and the voltage of its cathode decreases to 40 volts. Thus, the voltage of the ignition electrode f_2 of tube BC cannot reach the ignition value (70 volts). With the third dialling pulse, the tube B_{13} ignites, so that the voltage of the ignition electrode f_2 of gaseous tube BB increases. Since the third dialling pulse is not followed by further pulses, the voltage of electrode f_2 can assume a value such that the tube BB becomes conductive, if the subscriber at station AB is not busy.

Assume now that the station AB is busy. One of the tubes (not shown), of which the cathodes are connected to the point B, is then in a conductive condition, so that the voltage of point B is either 40 volts or 27 volts, according to whether the subscriber at station AB is dialling or is otherwise busy. When the voltage of the ignition electrode f_2 of tube BB has increased to 80 volts, only a voltage of 40 volts or 53 volts, i. e. a voltage lower than the ignition voltage, is set up between the ignition electrode f_2 and the cathode k , so that tube BB cannot ignite.

The subscriber at station AA then receives busy tone. A tapping point S on the inductor L_1 is connected by way of capacitor C_8 and a rectifier g_1 to one extremity of a winding of a transformer TG, the other extremity of which is connected to a source of supply V_8 , the voltage of which is 20 volts. Another winding of transformer TG is connected to a common busy-tone generator GB. The junction between capacitor C_8 and rectifier g_1 is connected by way of resistor R_{3d} to the point W. So long as the counting circuit MS is in its normal position, the voltage of the point W is equal to earth potential and rectifier g_1 is cut off. However, if one of the tubes of the counting circuit MS is conductive, the voltage of point W is 40 volts and rectifier g_1 is conductive. The generator GB then supplies busy tone to subscriber AA by way of rectifier g_1 , capacitor C_8 , inductor L_1 , tube BA and transformer TA.

When the subscriber at station AA, after his call has not been answered, replaces his receiver, a strong positive pulse is produced in the secondary winding of the transformer TA due to the line loop being opened. As a rule, this closing pulse is of such strength that the tube BA extinguishes, so that a strong positive pulse occurs at points Q. If, for example, as a result of a high resistance of the line, the pulses at point A were not sufficiently strong to extinguish the tube immediately, the tube transfers the pulse to point Q, so that even in this case a strong positive pulse occurs at point Q. The closing pulse is transferred by tube B_1 with opposite polarity to the point U and thence transferred by way of a capacitor C_5 and a rectifier g_2 to the cathode of tube B_3 . The ignition electrode f of tube B_3 is connected to a source V_5 of a voltage such that tube B_3 ignites if a strong negative pulse such, for example, as occurs when the receiver is replaced, is supplied to the cathode, but cannot become conductive with a comparatively weak pulse such, for example, as occurs with a dialling signal. When tube B_3 ignites, the voltage of the cathode greatly increases and a strong positive pulse is supplied by way of a capacitor C_6 to the ignition electrode f of tube B_2 , which ignition electrode is connected by way of resistor R_8 to a source V_6 of a voltage such that tube B_2 becomes conductive. Consequently, the potential of the anode a of this tube decreases and a strong negative pulse is supplied by way of a capacitor C_7 and inductor L_1 to the anode a of tube BA, as a result of which this tube extinguishes, if it had not already been extinguished immediately by the pulse at the point A. Furthermore, due to the ignition of tube B_3 , a strong positive pulse is supplied by way of rectifier g_2 and capacitor C_5 to the point U and thence transferred by way of capacitor C_2 , to the ignition electrode f of tube B_4 and by way of capacitor C_3 and resistor R_5 to the ignition electrode f of tube B_5 . The tubes B_4 and B_5 are thus ignited. Tube B_4 ignites somewhat later than tube B_5 , since the pulse to the ignition electrode of tube B_5 is somewhat retarded by the presence of the network R_5 , C_4 . The ignition of tube B_4 causes a subsequent tube in the counting circuit MS to become conductive in the manner which has already been described. However, a tube which couples point P to another subscriber's line cannot thus ignite, since tube B_5 also becomes conductive a short time after

tube B_4 . The ignition of tube B_5 results in a strong positive pulse at point W, by which the voltage of the cathode of the conductive tube in the counting circuit is suddenly increased to such extent that this tube extinguishes and the counting circuit MS is returned to its normal position. The tubes B_2 , B_3 , B_4 , B_5 re-extinguish automatically after their ignition due to the presence of the impedances Z_2 , Z_3 , Z_4 , Z_5 in their cathode leads. All gas-filled tubes are thus extinguished and the circuit is returned to its normal position.

As mentioned before, the potential of point Q decreases by 40 volts when subscriber AA is calling due to the tube BA becoming conductive. Consequently, tube B_1 supplies a strong positive pulse to the point U, so that tube B_2 ignites and, furthermore, tube B_{11} in the counting circuit MS becomes conductive, similarly as with reception of the first dialing pulse. However, the positive pulse at point U is now of such strength that the tube B_5 ignites, due to which tube B_{11} immediately extinguishes again, as described above. The rectifier g_2 prevents the positive pulse at the point U from being transferred to the ignition electrode f of tube B_2 . The pulse which occurs at point Q upon calling, in contradistinction to dialling pulses, does not result in the ignition condition of the tubes of the counting circuit MS being permanently varied.

Assume now that the subscriber being called is not busy. The ignition of the tube B_{13} then causes the tube BB to become conductive with the third dialling pulse, since the voltage of the cathode of the tube BB is now equal to earth potential. The current flowing through the main discharge path between cathode k and anode a of tube BB causes an increase in the potential of point Q up to 27 volts, so that the subscriber's line is marked busy and can no longer be reached by way of another connecting circuit, as has been explained above. Furthermore, the potential of point Q decreases further, so that tube B_1 transfers a positive pulse to the point U, which causes ignition of the tubes B_4 and B_5 , so that a subsequent tube in the counting circuit MS ignites, but immediately extinguishes again due to the ignition of tube B_5 . Since the counting circuit has thus returned to its normal position, the potential of point W is equal to earth potential and rectifier g_1 is cut off, so that busy tone is not supplied to the subscriber at station AA. During dialling, busy tone may be supplied to the subscriber's station but it cannot be heard by him, since his apparatus is designed in known manner to be such that the receiver is short-circuited during dialling.

If the subscriber at station AB takes up the receiver to answer the call, the closure of the line loop results in a negative voltage pulse at the point P, which is transferred by way of inductor L_1 to the point Q and is further transferred by tube B_1 with opposite polarity to the point U. The positive pulse at the point U causes ignition of the tubes B_2 and B_3 in the manner already described, so that tube B_{11} becomes conductive and immediately extinguishes again due to the ignition of tube B_5 . The desired connection between the subscribers at stations AA and AB is thus established and intelligence currents may be transmitted in either direction by way of transformer TA, the main discharge paths of tubes BA, BB and transformer TB.

When after the call is over, one of the subscribers replaces down the receiver, a strong positive closing pulse is transferred to the point Q with the result that the tubes BA and BB are extinguished in the manner already described and the circuit returns to its normal condition.

70 What we claim is:

1. An electronic dialing circuit in automatic signaling system for numerically establishing a connection between one of a plurality of apparatus of a first kind and one of a plurality of apparatus of a second kind comprising a first multiplied point coupled with each apparatus of said first kind, a first impedance interposed between said first multiplied point and a first terminal of a source of supply, a second multiplied point coupled with each apparatus of said second kind, a plurality of gas-filled tubes having ignition electrodes, said tubes being parallelly connected and interposed between said second multiplied point and said first multiplied point, a second impedance interposed between said second multiplied point and a second terminal of said source of supply, the difference in potential between said first and second termi-

nals of said source of supply being lower than the ignition voltage and higher than the operating voltage of said gas-filled tube, a calling line providing intelligence currents and dialing pulses coupled to said first multiplied point, said apparatus of the first kind including an electronic counting circuit having a plurality of output marking points and means coupled to said first multiplied point for applying impulses of a determined polarity to said counting circuit, said plurality of output marking points having a voltage which is controlled by said counting circuit as a function of said impulses and a plurality of integrating networks, each of the ignition electrodes of said gas-filled tubes being coupled to one of said integrating networks, said marking points being coupled to the ignition electrodes of said gas-filled tubes through the respective integrating network, said counting circuit having any of a normal condition and a plurality of electrical counting conditions and passing to a subsequent counting condition when one of said impulses is applied to said counting circuit, each counting condition having a voltage at one of said output marking points which is higher than the voltage required to ignite one of said gas-filled tubes when said tubes are inactive.

2. An electronic dialing circuit, as set forth in claim 1, wherein said means for applying impulses includes an amplifier and a pulse limiting circuit coupled thereto.

3. An electronic dialing circuit, as set forth in claim 1, further including means for restoring said counting circuit to its normal condition, said means responding when a pulse of a strength exceeding a predetermined threshold value occurs at said first multiplied point, said threshold value being higher than the maximum value of said dialing pulses.

4. An electronic dialing circuit, as set forth in claim 3, wherein said counting circuit comprises a plurality of additional gas-filled tubes and a common impedance coupled to the outputs of said additional tubes and a further gas-filled tube having a control electrode coupled to said first multiplied point and an output electrode coupled to said common impedance.

5. An electronic dialing circuit, as set forth in claim 3,

5

wherein said means for restoring said counting circuit to its normal condition responds to a pulse which occurs at the first multiplied point upon ignition of one of said plurality of gas-filled tubes.

6. An electronic dialing circuit, as set forth in claim 1, further including a busy tone generator and a circuit element coupling said generator to said first multiplied point, said circuit element being controlled by said counting circuit to provide busy tone to said first multiplied point only when said counting circuit has a condition other than the normal condition.

10 7. An electronic dialing circuit, as set forth in claim 2, further including means coupled to said first multiplied point and responsive to a first pulse of opposite polarity to that to which said counting circuit responds, said latter means supplying a second pulse to said first multiplied point for extinguishing one of said plurality of gas-filled tubes, said second pulse having the same polarity as that to which said counting circuit responds and having a strength exceeding a predetermined threshold value, said threshold value being higher than the maximum value of said dialing pulses.

15 8. An electronic dialing circuit, as set forth in claim 7, wherein said latter means includes said amplifier coupled to said first multiplied point, a first auxiliary gas-filled tube having a first cathode, a rectifier interposed between said amplifier and said cathode, a second auxiliary gas-filled tube having a second cathode, an ignition electrode coupled to said first cathode and an anode coupled to said first multiplied point, and an impedance coupled to the cathodes of each of said auxiliary tubes whereby said auxiliary tubes operate in an unstable manner.
